SNUBBED SPRING GROUP

Walter L. Schlegel, Jr., Chicago, Ill., assignor to American Steel Foundries, Chicago, Ill., a corporation of New Jersey

Application April 8, 1952, Serial No. 281,104
11 Claims. (Cl. 267—9)

The invention relates to a spring group utilized to resiliently support the bolster of an associated railway car truck, and more particularly to a novel snubbing device associated therewith.

A general object of the invention is to provide a spring group with a snubbing device operative to frictionally resist relative vertical and horizontal movements of the group.

Another general object of the invention is to provide a spring group wherein direct wedging action between the friction shoes is operative to actuate the associated snubbing device.

A more specific object of the invention is to provide a spring group and a related snubbing device wherein the friction surfaces and associated friction shoes are supported from the same plate.

Still another specific object of the invention is to provide a spring group having an associated friction device that will automatically compensate for wear on the operative friction surfaces.

Other objects of the invention will become apparent in the course of the following description and from an examination of the drawings, wherein:

Figure 1 is a fragmentary side elevational view of one embodiment of the invention;

Figure 2 is a sectional view of the invention taken along line 2—2 of Figure 1, and

Figure 3 is a fragmentary plan view of the invention taken along lines 3—3 of Figure 2.

Describing the preferred embodiment of the invention in detail, the group consists of a top plate 2 having a flange 4 depending therefrom and defining spring seats 6 quadrantly disposed on the lower side of said plate. Centrally of the plate and disposed transversely thereof on its lower side, a friction surface 8 is formed, the function of which is hereinafter more fully described.

A lower plate 10 is aligned vertically and below the top plate 2 and comprises the upstanding flanges 12, 12, which peripherally define spring seats 14 quadrantly disposed on the upper side of said lower plate. Coiled springs 15, preferably arranged in sleeved sets of opposed helical construction, are seated at opposite ends on the spring seats 6 and spring seats 14 of the upper and lower plates, respectively, thereby affording resilient connection between said plates.

Lugs or bosses 16 and 18 are formed on the remote faces of the upper and lower plates and offer connection means to attach the spring group to an associated side frame and bolster of a railway car truck, the spring group being operative to resiliently support said bolster.

Centrally of the lower plate 10 and transversely disposed thereon, a pocket 20 preferably of rectangular form may be formed comprising the transverse walls 22, 22 with the longitudinal walls 24, 24 integrally connecting the opposite ends thereof. The longitudinal walls 24, 24 present on the inboard faces thereof, the vertical friction surfaces 26, 26 herein shown as planed surfaces, but, as well known to those skilled in the art, may be of other form such as crowned construction.

The friction shoes 28 and 30 are preferably disposed intermediate the friction surfaces 26, 26 and partly embraced by the pocket 20. The friction shoe 28 presents the vertical face 32 engaging one of the friction surfaces

2

26 of the lower plate 10, and the horizontal face 34 engaging the friction surface 8 of the upper plate 2. A recess or spring seat 36 with a downwardly facing opening is formed within the shoe 28 to receive and seat one end of the supporting coiled spring 38, the spring extending downwardly to seat and compressively abut the lower plate 10. The action of the spring 38 firmly engages the shoe 28 with the friction surface 8 of the upper plate 2. The inboard side of the shoe 28 is arranged to present the wedge surface 40, so disposed as to be obliquely related to the faces 32 and 34 of said shoe, hence to be in the same relation to the cooperating friction surfaces 26 and 8.

The other friction shoe or, more appropriately, wedging shoe 30 presents the vertical face 31 abutting the other friction surface 26. A recess or spring seat 44 with a downwardly facing opening is formed within the wedging shoe 30 and is arranged to receive and seat the coiled spring 45, the spring extending downwardly to compressively seat upon the lower plate 10. A wedge surface 46 is formed on the inboard side of the shoe 30 and is in complementary slidably engagement with the oblique or inclined surface 40 of the friction shoe 28. The spring 45 is operative to urge the shoe 30 upwardly and into contact with the shoe 28 and along the surface 40 formed thereon. The action thus induced is of a wedging nature forcing both shoes outwardly and, due to the inclined planed engagement therebetween, into pressured contact with the related friction surfaces 26, 26.

It is to be noted that in the arrangement shown and described the action of the wedging shoe 30 is also operative to urge the shoe 28 upwardly and into engagement with the friction surface 8 of the upper plate 2. Hence, if the spring 38 becomes inoperative due to failure or other reason, the snubbing device would still function.

In operation the relative vertical movement between the plates 2 and 10 of the spring group causes relative outward movement between the shoes 28 and 30 in response to the sliding action along the area of inclined engagement. The force urging the shoes outwardly is translated into pressure engagement between the shoes and friction surfaces, thus snubbing or choking the vertical movement between the plates. Horizontal leftward movement of the top plate 2 relative to the bottom plate 10, as seen in Figure 2, is resisted by the frictional engagement between the shoe 28 and the friction surface 8 and between the shoe 30 and the related friction surface 26 as the mentioned movement urges the shoe 28 into wedged engagement with the shoe 30 forcing same downwardly along the related friction surface 26. Horizontal movement of the plate 2 to the right, as seen in Figure 2, is resisted by the frictional engagement between the shoe 28 and the friction surface 8. Similarly horizontal movement of the top plate 2 to the left or right, as seen in Figure 1, is resisted by the frictional engagement between the shoe 28 and the friction surface 8.

As wear occurs between the operating friction surfaces 26 and 8 and the related faces of the friction shoes 28 and 30, automatic compensation is made by the shoes taking up a new static position relative to each other and to the associated friction surfaces. It should be mentioned that the shoe 28 may, if desired, be fixedly secured to the top plate 2 and the wedging action of the shoe 30 will still enable the device to frictionally snub relative vertical movement between the plates. However, such a construction will not offer the horizontal snubbing action of the preferred embodiment described above.

I claim:

1. In a spring group, spaced resiliently movable plates, one of said plates carrying friction surfaces upstanding therefrom, friction shoes disposed intermediate said surfaces and engaging same, an area of engagement between

said friction shoes delineating a plane having an inclined relation to said surfaces, spring means consisting of coiled springs having ends seated on said one plate, said springs directly engaging both of said friction shoes on the ends opposite the mentioned ends, whereby said shoes are urged away from said one plate and at least one of said shoes is urged to directly engage the other of said plates.

2. In a spring group, spaced plates flexibly movable toward and away from each other, a friction device disposed intermediate said plates operative to snub relative movements therebetween, said device consisting of a plurality of parallel friction surfaces on one of said plates, friction shoes disposed to engage said friction surfaces, each of said friction shoes having angularly related surfaces, one of which engages the related friction surface and the other of which abuts the other friction shoe, spring means flexibly supporting said friction shoes comprising an individual spring directly engaging each shoe, and connection means between said shoes and the other of said plates, whereby relative movement of said other plate causes movement between said shoes along certain of the angularly related surfaces.

3. In a spring group having spaced plates with interconnecting coiled springs, the combination of at least one friction surface connected to one of said plates, at least one friction shoe connected to the other of said plates and engaging said surface, a wedging shoe in wedged engagement with said one shoe and said one plate, spring means comprising one spring engaging said wedging shoe and said one plate and operative to maintain wedged engagement between said friction shoe and said wedging shoe, and another spring engaging said one shoe and said one plate and operative to maintain the connection between said one shoe and said other plate.

4. In a spring group having spaced interconnected plates, upstanding walls integral with one of said plates and forming a boxlike pocket thereon, friction surfaces on the inboard faces of certain of said walls, friction shoes disposed substantially within said pocket and engaging said surfaces, a spring resiliently engaging each shoe, said shoes being provided with wedge surfaces, said wedge surfaces cooperatively engaging each other in a wedge disposed diagonally of the pocket, and a direct connection between said shoes and the other of said plates, whereby vertical movement of said other plate causes relative movement between said shoes along said wedge surfaces.

5. In a spring group, spaced plates with interconnecting coiled springs, friction surfaces on one of said plates, a friction shoe directly engaging one of said friction surfaces and the other of said plates, an independent coiled spring disposed between said one plate and said shoe and directly engaging said shoe, a wedge surface on said shoe remote from said one friction surface and said one plate and in oblique relation therewith, another friction shoe disposed between said wedge surface and the other of said friction surfaces, and another independent coiled spring compressed between and engaging said other friction shoe and said one plate operative to urge said other shoe into wedged engagement with said wedge surface and said friction surface.

6. In a spring group spaced plates flexibly movable toward and away from each other, vertical inboardly facing friction surfaces disposed transversely on one of said plates, a friction shoe associated with each of said surfaces, an area of inclined planed engagement between said shoes, and spring means urging said shoes upwardly and at least one of said shoes into engagement with the other of said plates, said spring means comprising an independent coil spring for each shoe compressed between said one plate and the related shoe.

7. In a spring group, spaced plates operatively movable toward and away from each other and flexibly interconnected by a plurality of coiled springs, a vertically disposed friction surface carried by one of said plates, a

horizontally disposed friction surface carried by the other of said plates, a friction shoe having normally related surfaces constantly engaging the horizontal friction surface and the vertical friction surface, respectively at all operative positions of the spaced plates, a wedging shoe, and spring means supporting said wedging shoe and urging it to abut said friction shoe and urge same into pressured engagement with the mentioned friction surfaces, said spring means comprising coil springs seated on said one plate and engaging their respective shoes along compressional axes normal to said one plate.

8. In a spring group, spaced plates interconnected by a plurality of coiled springs, spaced parallel vertically disposed friction surfaces on one of said plates, another friction surface on the other of said plates, friction shoes slidably engaged between said parallel surfaces, one of said shoes engaging said other surface, said friction shoes having an area of common engagement defining a plane obliquely related to said friction surfaces, a coiled spring seated on said one plate supporting one of said friction shoes and maintaining same in engagement with said other surface, and another coiled spring seated on said one plate engaging the other of said friction shoes and operative to wedge said friction shoes into engagement with said parallel friction surfaces, the compressional axes of said springs being normal to the plane of said other surface.

9. In a spring group, spaced flexibly interconnected plates, friction surfaces on one of said plates, friction shoes associated with friction surfaces and engaging each other along a plane having an inclined relation to the surfaces, one of said shoes being connected to the other of said plates, and the other of said shoes being without connection thereto, and spring means on said one plate engaging said friction shoes and urging same outwardly into engagement with said friction surfaces, said spring means comprising a separate spring directly engaging each shoe.

10. In a spring group having spaced resiliently interconnected plates and a friction device disposed therebetween, the combination of spaced friction surfaces on one of said plates, another friction surface on the other of said plates, a friction shoe disposed intermediate said friction surfaces, another friction shoe disposed intermediate said friction surfaces and in inclined planed engagement with the first mentioned friction shoe, and spring means engaging said shoes and operative to maintain said shoes in engagement with all of said friction surfaces, said spring means comprising a pair of coiled springs compressively engaging at adjacent ends thereof said one plate and each of said shoes, respectively.

11. In a spring group, spaced plates operatively movable toward and away from each other and interconnected by a plurality of coiled springs, a friction surface on each plate, a friction shoe having normally related surfaces constantly engaging said friction surfaces, a wedge shoe disposed intermediate one plate and said friction shoe, and a pair of springs reacting between said one plate and their respective shoes along compressional axes normal to the plane of said one plate operative to urge said wedge shoe into wedge engagement with the friction shoe and said one plate and to maintain the friction shoe in pressured engagement with the friction surfaces at all operative positions of the spaced plates.
